UNITED STATES PATENT OFFICE.

FLOYD H. PHILLIPS AND CARL E. MANN, OF BUFFALO, NEW YORK, ASSIGNEES TO
QUEEN CITY PRODUCTS, INC., OF BUFFALO, NEW YORK.

KNITTED CAP.

Application filed April 6, 1926. Serial No. 100,057.

This invention relates to improvements in knitted caps of that kind generally known as muffler caps, and which are provided with a crown portion, a band or portion encircling the lower part of the crown, and tabs or muffler portions secured to the band. These tabs are adapted to occupy either a folded-up position against the crown of the cap or to be turned down with the band, or a part 10 of said band, and usually have their ends buttoned or otherwise fastened together beneath the chin of the wearer.

The objects of the invention are to produce a knitted cap of this kind having the crown and the band knit in one piece, the band being formed by folding up the extended lower portion of the crown, whereby the usual seam between band and crown is omitted and a more elastic and better 20 fitting cap is provided; also to form the knitted fabric of which the cap is made with a different kind of stitching on each face thereof whereby the band will provide a decorative part in contrast with the crown.

Other objects are to provide a cap of this sort having the flaps formed of fabric adapted to harmonize with the band and contrast with the crown in the same manner as the band; also to sever or cut the band of the 30 cap in a novel manner and without waste to provide a diagonal attaching edge for each flap, and so that the remaining edge of each cut can be secured to the crown to form a neat finished appearance when these 35 edges are exposed by turning down the flaps; also to so attach said last mentioned edges of the band to the crown as to strengthen the band and form a seam between said edge and said crown which will act to prevent 40 undue stretching of and consequent injury to the crown.

Other objects are to improve the construction and production of knitted muffler caps in the other respects hereinafter set 45 forth.

In the accompanying drawings,

Fig. 1 is a side view of a knitted muffler cap embodying our invention, showing the band and flaps thereof in folded position.

Fig. 2 is a similar view thereof, partly broken away, showing the flaps and the back part of the band turned down for use as a muffler.

The cap illustrated in the drawings comprises a crown portion 10, a band 11 en-

circling the lower portion of said crown and having a front part 12 and back part 13. The cap also has opposite side flaps 14, which, when folded up, are secured by button holes 15 to buttons 16 on the crown, as 60 usual, see Fig. 1. When used as a muffler, the flaps 14 and the back part 13 of the band are turned down, as shown in Fig. 2, and the ends of the flaps are then buttoned or otherwise secured together under the chain 65 in the usual manner.

In accordance with the invention, the crown 10 and band 11 are made from a single piece of knitted fabric formed with different or contrasting stitching or knitting 70 on its opposite faces. For example, the outer face of the fabric may comprise half cardigan stitch 18, while the inner face is rack knitted as shown at 19. Consequently, after the material has been cut to form the 75 crown 10, and the lower part of the piece of material has been turned outwardly and upwardly against the crown, a band 11 is provided which contrasts with or has a different appearance to that of the crown, resulting 80 in a cap of distinctive appearance.

By making the crown of the cap and the band in one piece, the lower part of the cap which is stretched around the head of the wearer is much more elastic than when the 85 crown and band are sewn together as was heretofore done. This not only affords greater comfort for the wearer but also makes it possible to use one size of cap for a larger number of different head sizes. 90

The flaps 14 are preferably produced from strips of material knit to match the band. In order to provide attaching edges for the flaps 14, so that each flap can extend at the desired angle to the band 11, the band is severed at each side of the cap on a diagonal line extending downwardly and forwardly from the top substantially to the bottom edges of the flap, thus forming the front and back portions 12 and 13, terminating in 95 adjacent diagonal edges 20 and 21 respectively. Each flap 14 is cut square or at right angles to its length across that end by which it is to be secured, thus providing a straight edge 22 which is stitched to an edge 21 of the band part 13. Thus, when the band part 13 and the flaps 14 are folded, these parts will be of contrasting appearance to the crown. 105

In order to provide a neat and finished appearance to the cap, particularly when 110

used as in Fig. 2, the diagonal edges 20 of the front part 12 of the band are preferably stitched to the crown, as shown, and since the half cardigan stitching of the crown produces substantially upright, straight ribs, the diagonal seam, formed by stitching said edges 20 to the crown, extends across several of said ribs, thus producing a strong connection adapted to prevent undue stretching or injury to the crown of the cap in use, as would be the case, for example, if the cuts in the band were made straight across said band, thus leaving upright edges which could only be secured by a seam extending along one or possibly two of the adjacent upright ribs of the crown.

10 A muffler cap, produced as above described, is neat and attractive in appearance, and by reason of the one piece construction of the crown and band and the diagonal cutting of said band, the cap is economically produced, without waste, and parts are provided to which the flaps can be readily attached.

15 We claim as our invention:—

20 1. A cap having a crown and a turned up band around the lower portion of said crown, said band being knitted in one piece with said crown and folded upwardly at the lower edge of the crown, said band being slit diagonally at opposite sides of said crown substantially from its upper edge to its connection with said crown, thus dividing said band into front and back portions, and flaps each having a straight edge connected to one diagonal edge of each slit and adapted to be turned down with the back portion of said band to form a muffler.

25 2. A cap having a crown and a turned up band around the lower portion of said crown, said band consisting of a single strip of material extending around the lower part of the crown and being slit diagonally at opposite sides of said crown substantially

30 from its upper edge to its connection with said crown, thus dividing said band into front and back portions, and a flap having an edge cut substantially at right angles to its length and connected to one diagonal edge of each slit and adapted to be turned down with the back portion of said band to form a muffler, said other diagonal edge of each slit being secured to said crown.

35 3. A cap having a crown and a turned up band around the lower portion of said crown, said band being slit diagonally at opposite sides of said crown, substantially from its upper edge to its connection with said crown, thus dividing said band into front and back portions having diagonal ends, and a pair of flaps each having an end cut substantially at right angles to its length and adapted to be secured to one of the diagonal ends of said back portion of said band, said flaps being adapted to be turned down therewith to form a muffler, and said diagonal ends of said front portion of said band being secured to said crown.

40 4. A cap having a crown and a turned up band around the lower portion of said crown, said crown and band being formed of a single piece of knitted fabric having contrasting stitching on its opposite faces, and said band being folded upwardly from the lower edge of said crown whereby said band and crown are produced without a seam, and said band is of appearance contrasting with said crown, said band being slit at opposite sides of said crown to provide a part which, when turned down, will harmonize with said crown, and also to provide attaching edges on said part, and flaps adapted to be secured to said attaching edges, said flaps being adapted, when folded, to harmonize with said band and contrast with said crown.

FLOYD H. PHILLIPS,
CARL E. MANN.
